UNITED STATES PATENT OFFICE.

TIMOTHY ROSE, OF CORTLANDVILLE, NEW YORK.

IMPROVED METHOD OF SEPARATING SAND FROM WATER IN WELLS.

Specification forming part of Letters Patent No. 57,974, dated September 11, 1866.

To all whom it may concern:

Be it known that I, TIMOTHY ROSE, of Cortlandville, in the county of Cortland, State of New York, have invented a new and useful improvement in the application of a device for separating the sand from the water in bored or sunk wells while pumping, and for keeping the bottom of the tube free from clogging by accumulation of sand within; and I do declare that the following is a full and exact description thereof, reference being had to the accompanying drawings and the letters of reference marked thereon.

The object named is accomplished by means of a strainer and smaller tube placed within the main tube at the bottom, and also a movable point inserted in the bottom of the outer tube, the stem of which is grooved, so as to permit the water and sand to pass out downward.

Figure 1 of the accompanying drawings represents a section of the essential parts of this device, in which *a a a a* is the main tube and *h h* the movable point. This point is conical below, and enters the tube by a stem about four or five inches. This stem is grooved, as represented in Fig. 2. On each side is a pin, *f*, working in a slot, *g*, permitting the point to descend one or two inches. This descent of the point is effected by withdrawing the tube a short distance after driving it down. When this is done the water and sand have a free passage through the grooves *k k*, as represented in Fig. 3. The object of this is to let the sand, which would otherwise accumulate in the tube, pass out.

The main tube is perforated with small holes *b b* for a distance of one or two feet. Inside of this main tube is fitted a smaller tube, *d*, held firmly in place by flanges *c c* inserted between the joints of the main tube, and so as to cut off the chamber below this joint from any communication with the tube above except through the smaller tube. This

smaller tube is likewise perforated with small holes *i i*, and is also surrounded and closed at the bottom by a fine strainer, *e e*, of wire-gauze or perforated metallic plate, or whatever substance may serve the purpose.

I am aware that wire-cloth has been used to strain the water; but when placed on the outside of the pipe it is liable to be broken and torn off in driving down, and experience shows it to be of little use.

I am aware also that wire-cloth and screens have been used on pumps for deep wells in various ways; but I am not aware that a strainer has been used between the two pipes, and having a space between it and the tubes on either side, whereby the motion of the water created by the action of the pump will serve to keep the strainer free from clogging by the sand; nor am I aware that in any previous devices there has been open passage for the water and sand through the bottom of the tubes, whereby the sand which may have entered the tubes will, by the action of the pump, as above named, be kept free, and will naturally find its way out through the grooves below, and thus prevent the liability of its accumulating within the tube.

I do not, therefore, claim as new the use of wire-cloth or its equivalent as a strainer or separator of sand from water; but

I do claim as my improvement and desire to secure by Letters Patent—

The combination of the inside tube, with the strainer of wire-cloth or its equivalent, and the flange to cut off the inferior chamber, together with the movable point, with the grooved stem, by which is secured open passage downward through the end of the main tube, substantially as herein described, and for the purpose set forth.

TIMOTHY ROSE.
